To all whom it may concern:

Be it known that I, Roman J. Thill, a citizen of the United States, residing at Rockford, in the county of Winnebago and State of Illinois, have invented a new, original, and ornamental Design for a Sewing Machine Cabinet, of which the following is a specification, reference being had to the accompanying drawing, forming part thereof.

In the drawing:

The figure is a perspective view of a sewing machine cabinet embodying my invention.

I claim:—

The ornamental design for a sewing machine

ROMAN J. THILL.
